[57] CLAIM

The ornamental design for a dental suction head, as
shown and described.

DESCRIPTION

FIG. 1 is a front elevational view of a dental suction
head showing my new design;

FIG. 2 is a right side elevational view thereof, the left
side being a mirror image;

FIG. 3 is a rear elevational view thereof.

FIG. 4 is a top plan view thereof.

FIG. 2

FIG. 1

FIG. 3

U.S. Patent
